UNITED STATES PATENT OFFICE.

JACOB J. DAUCH AND WILLIAM F. HARBRECHT, OF SANDUSKY, OHIO.

STRAW-COOKER.

No. 878,711.

Specification of Letters Patent.

Patented Feb. 11, 1908.

Application filed July 26, 1906. Serial No. 327,812.

To all whom it may concern:

Be it known that we, JACOB J. DAUCH and WILLIAM F. HARBRECHT, both citizens of the United States, residents of Sandusky, county 5 of Erie, and State of Ohio, have invented a new and useful Improvement in Straw-Cookers, of which the following is a specification, the principle of the invention being herein explained and the best mode in which 10 we have contemplated applying that principle, so as to distinguish it from other inventions.

Our invention relates to improvements in pulp-digesters and particularly in those used 15 in cooking straw which material is extensively used in the manufacture of straw-board and certain kinds of wrapping papers. Obviously however, in the use of our cooker the character of the stock is immaterial and 20 such cooker may be employed in the digesting of rags and the like as well as straw and other materials with equally satisfactory results.

The invention is concerned particularly 25 with the arrangement of and manner of supply of the steam distributing pipes, within the boiler or shell of the cooker, the object being to provide a simple valve construction for supplying steam to the submerged pipes 30 only, and to so dispose the apertures whereby the steam escapes from such distributing pipes as to insure the thorough inter-mixture of the contents of the cooker.

Said invention, then, consists of means 35 hereinafter fully described and specifically set forth in the claims.

The annexed drawing and the following description set forth in detail certain means embodying the invention, such disclosed 40 means constituting but one of various mechanical forms in which the principle of the invention may be used.

In said annexed drawing:—Figure 1 represents a longitudinal axial cross-section of a 45 cooker embodying my invention; Fig. 2 represents a transverse vertical cross-section of the valve whereby steam is supplied to the steam distributing pipes of such cooker; and Fig. 3 shows a transverse cross-section of one 50 of the steam-distributing pipes and the adjacent portion of the cooker wall.

In said figures, A designates the tank or boiler of our cooker which is shown as being of the approved spherical or globular form.

Such tank is rotatably supported at diametrically opposite points upon gudgeons or trunnions a' securely attached to the boiler shell and turning in suitable bearings a . Of such bearings, however, and corresponding supports a^2 of timber or other material, but 60 one appears in the figures. The means whereby rotation is imparted to the tanks are likewise omitted, since they form no part of this present invention. As shown in Fig. 1, the tank has been partially rotated from 65 its normal, or charging, position so that the manhole a^3 , through which access is had to the interior of the tank, appears on the farther side of the half section.

The general process of cooking paper 70 stock, it is taken, is well enough understood not to require extensive explanation here. It will, hence, suffice to say, that preparatory to the operation, the straw, rags or other stock is introduced into tank A through man-hole a^3 , along with a quantity of "cooking liquor" of maximum strength. Such liquor it is understood comprises a solution of chemicals adapted to effect a disintegration of the material being treated. Live steam 80 under pressure is thereupon admitted into the tank and the latter at the same time is rotated so as to agitate its contents and insure contact of the chemical "cooking liquor" with every portion of the stock. It 85 is to the means that we employ for introducing the steam that it is desired to here call particular attention. For this purpose, one of the trunnions a' upon which the tank is mounted is formed with an axial aperture 90 or bore a^4 , and the portion of the boiler shell opposite the inner end of this bore is cut away. In the opening in the shell thus formed, is mounted a valve-casing B of the general cylindrical form illustrated in 95 Figs. 1 and 2. Such casing B is provided, equidistantly spaced about its cylindrical face, with a plurality of openings b . Into these openings are screw-threaded the ends of steam-distributing pipes B' that are 100 meridionally disposed within the boiler, being attached to the inside of the walls of such boiler by means of clips b' and having their outer ends, which converge towards the portion of the boiler opposite to valve-casing B, 105 closed by means of caps b^2 . The steam escapes from distributing pipes B' through small openings b^3 that are arranged in stag-

gered order on the side of the pipes turned towards the boiler wall. To indicate still more definitely the preferred disposition of these apertures b^3 they may be described as 5 being alternately located on opposite sides of a line drawn longitudinally along the pipe on its outer face and at an angle laterally divergent therefrom of about forty-five degrees. This construction quite clearly appears in Fig. 3.

The steam for steam-distributing pipes B' is received through a pipe B^2 connected at its outer end with a suitable source of supply and extending inwardly through the bore a^4 15 in trunnion a' so as to terminate within valve-casing B . A stuffing box a^5 and gland a^6 provide a bearing for the outer end of supply pipe B^2 , which obviously remains stationary while the tank revolves. Fitting within 20 valve-casing B , and screw-threaded, or otherwise securely mounted upon the inner end of supply pipe B^2 , is a cylindrical valve b^4 . As shown in Figs. 1 and 2, valve b^4 is provided with a port b^5 adapted to uncover 25 at any one time the ends of but two distributing pipes B' , which it will be remembered are connected with opening b in valve-casing B . As appears in Fig. 2 the disposition of valve b^4 is such as to turn port 30 b^5 directly downwardly, as a result of which it is seen that steam is supplied to the two lowermost of distributing pipes B' only, that is to the ones that are successively submerged by the semi-liquid contents of the 35 boiler as the latter rotates on its axis.

The general mode of operation of our improved straw-cooker has been incidentally set forth in connection with the description given of its structure. In conclusion then it 40 remains to state what are the new results attained by our improvements. First of all it should be remarked that we do not set up as broadly new the regulation of the supply of steam to distributing-pipes B' so as to cut 45 off all but those that are submerged. We do, however, set up the construction of the valve whereby this result is achieved as being simpler in construction and operation than any heretofore devised for this purpose so 50 far as we are aware. By the arrangement of the apertures b^3 in distributing pipes B' , the steam as it escapes from the submerged pipes to which it is thus supplied, is first directed downwardly, or outwardly against 55 the walls of the boiler. The results secured by this method of operation are highly valuable in that the collection of sediment as well as of stock unaffected by the chemicals in the "cooking liquor" along the walls of 60 the boiler is prevented, since the escaping jets of steam are made to penetrate to the very bottom of the mass and in rising per-

meate the whole. A uniform, as well as thorough cooking of the stock is thus effected.

Having thus described our invention, that 65 which we particularly point out and distinctly claim, is:—

1. In a pulp-digester, the combination with a rotary boiler, of meridionally arranged steam-distributing pipes within said rotary boiler and disposed against the inside of the walls thereof, said pipes being respectively provided with apertures for the escape of steam on the side adjacent to the tank-walls only.

2. In a pulp-digester, the combination of a rotary boiler, a steam supply pipe, a series of meridionally arranged steam-distributing pipes within said boiler, said pipes being connected with said supply pipe and being respectively provided with apertures for the escape of steam on the side adjacent to the walls only of said rotary boiler, and a valve controlling connection between said supply pipe and said distributing pipes, said valve 85 being adapted to connect such supply pipe with a plurality of distributing pipes successively submerged in the course of said boiler's rotation.

3. In a pulp digester, the combination of a spherical boiler rotatably mounted upon trunnions, one of said trunnions being provided with an axial bore, a cylindrical valve-casing fitted in a recessed portion of one of the trunnions and having one end closed and mounted with the other open end over the inner end of such bore, a plurality of meridionally arranged steam-distributing pipes within said boiler, each pipe having apertures for the escape of steam on the side adjacent 100 to the walls only of said rotary boiler, said pipes being connected with said valve-casing, a steam supply pipe mounted in the bore in said trunnion and extending within said valve-casing, and a cylindrical valve mounted within said casing and connected with said supply pipe, said valve being provided with a port disposed to connect said supply pipe with a plurality of distributing pipes 105 successively submerged in the course of said 110 boiler's rotation.
